UNITED STATES PATENT OFFICE

151,062

DESIGN FOR A SCALE

David A. Meeker, Troy, and Kenneth C. Allen,
Dayton, Ohio, assignors to The Hobart Manufacturing Company, Troy, Ohio, a corporation of Ohio

Application June 7, 1946, Serial No. 130,492

Term of patent 14 years

(Cl. D52—10)

To all whom it may concern:

Be it known that we, David A. Meeker and Kenneth C. Allen, citizens of the United States of America, residing at Troy, in the county of Miami and State of Ohio, and at Dayton, county of Montgomery, State of Ohio, respectively, have invented a new, original, and ornamental Design for Scale, of which the following is a specification, reference being had to the accompanying drawing, forming a part thereof, and in which

Fig. 1 is a perspective view from one side of a scale, embodying our new design;

Fig. 2 is a perspective view from the other side thereof; and

Fig. 3 is a side elevational view of the same.

The design is characterized by having a generally rectangular base on which a platter is received, the base having a rearward narrow up-

wardly extending portion supporting an overhanging chart casing.

We claim:

The ornamental design for a scale, substantially as shown and described.

DAVID A. MEEKER.
KENNETH C. ALLEN.
